METHOD AND MACHINE FOR MAKING FLEXIBLE DUCT CONNECTOR STOCK AND RESULTANT PRODUCT

Martin M. Gracer, 71 Laurel Drive,
Massapequa Park, N.Y.
Filed July 9, 1959, Ser. No. 825,954
3 Claims. (Cl. 161—36)

This invention relates to flexible connector stock and machine and method for making the same.

My invention is a continuation in part of my application Serial No. 470,203, filed by me on November 22, 1954, now abandoned, and deals with the provision of improvements thereover and novel methods for making the same.

In my application aforesaid, I have provided a flexible duct connector stock for joining the ends of ducts to provide a flexible seal as between a blower or furnace and the duct leading therefrom in which two elongated lengths of sheet metal strips and a length of duct sealing fabric are joined in the composite so that each of said metal strips is joined to the opposite side edges of the fabric. Specifically, in said application, the juncture between the fabric and the metal is formed by double folds, bending the metal into a flat tubular convolute of at least about one and one-half turns, and double clinched in this condition by flattening the same during folding. Such composite of two strips of metal and a single web between them is then formed into a duct outline, either round or rectangular, to extend the opposite strips for juncture with permanent duct installations, to align the duct and a blower or furnace to accommodate for dimensional aberrations, to absorb objectional vibrations which might be transmitted through the length of the ducts. Stock for making such connectors is supplied to the market in extended lengths or coils of from fifty to one hundred feet, from which sections are cut off in the field for use. These coils are, in a measure, cumbersome to handle in that if coiled into a roll of too small a radius, the product will assume a permanent set when bent above the elastic limit of the composite and there then is involved the work of malleting, to take out the creases or waviness.

While other transverse bending stresses to which the composite above described is subjected, such as in the formation of duct outlines by inner and outer folds, do not relax the clinching between the metal and fabric by reason of the double fold in accordance with my prior application, a degree of inflexibility is experienced which involves unnecessary, high labor costs for handling.

I have found that in a connector in accordance with my present invention, I may beneficially retain a joint between the strips of metal and the composite edges of the duct sealing fabric employing a double fold in accordance with my prior invention whereby, in the extended condition of the metal strips in respect to the common fabric, abrasion of the fabric by the metal is avoided, securing other economies in package size of the stock and labor handling costs to form duct outlines transversely bent either at sharp angles or in gradual curves, employing heavy gauge sheet metal, by forming weakened areas along the folds in the composite where they are formed to clinch the metal to the fabric. Specifically, by providing transverse cutouts or scores, so that in retaining the benefits of a tubular convolute in clinching the metal to the fabric on its opposite edges, a more intimate engagement may be effected between metal and fabric by scoring the sheet which forms a portion of the convoluted edge, thereby securing, in the formation of a coil of the stock, a more compact and economical package.

Still more particularly, it is an object of my invention to provide a flexible connector stock having uniformly

2

shaped metal strips connected to opposite edges of a length of duct sealing fabric employing, at the metal strip side edges, a double fold, resulting in a tubular convolute of more than one turn, in clinched engagement with the fabric and which may be handled in overlapped condition of the three components of metal and fabric economically and efficiently, and be readily severed when required, with the same ease as a thinner stock.

Still more particularly, it is an object of my invention to provide a length of flexible connector stock composed of duct sealing fabric joined on its opposite edges by metal strips having double folds to clinch the fabric and metal to each other, in which a warped condition is minimized, if not entirely, eliminated, in which economy in space is effected, package sizes of long lengths are reduced, strong grip between fabric and metal is assured and accuracy in handling is enhanced.

Still more particularly, it is an object of this invention to provide a highly efficient method and apparatus for forming connector stock, while effecting economies in production, storage and power forces in combining the layers of metal and fabric into clinching engagement to produce a double edge fold of metal to opposite sides of a duct sealing stock of fabric.

To attain these objects and such further objects as may appear herein or be hereinafter pointed out, I make reference to the accompanying drawing, forming a part hereof, in which—

FIGURE 1 is a fragmentary perspective view showing the components entering into the stock in accordance with my invention;

FIGURE 2 is a sectional view showing an initial condition of juncture of the components shown in FIGURE 1;

FIGURE 3 is a sectional view showing the final condition of fold of the components shown in FIGURE 1;

FIGURE 4 is a plan view in the direction of the arrows 4—4 of FIGURE 3, with the parts overlapped ready for packaging;

FIGURE 5 is a fragmentary section taken on the lines 5—5 of FIGURE 4;

FIGURE 5a shows a coil of the product;

FIGURE 6 is a perspective view of the ultimate product, ready for bending transversely;

FIGURE 7 is a section taken on the lines 7—7 of FIGURE 6;

FIGURE 8 is a perspective view of an oblong form of duct made from the connector in accordance with my invention, with an inside fold of fabric;

FIGURE 9 illustrates a cylindrical form of duct in accordance with my invention, with an outside fold of fabric;

FIGURE 10 is a longitudinal diagrammatic side elevation of a means of forming the product in accordance with my invention;

FIGURE 10a is a fragmentary plan view of the positions of the strips when punched;

FIGURE 11 is a magnified fragmentary plan view of the aligning and metering components;

FIGURE 12 is a section taken on the lines 12—12 of FIGURE 10;

FIGURES 13 to 21 are side elevations, with work in section, showing the forming rolls in progressive steps in making the double edge fold of the composite in accordance with my invention.

Making reference to the drawing, a flexible connector stock in accordance with my invention is provided from a length of duct sealing fabric 10 and strips of sheet metal 11 and 12, different widths of such strips being employed, if desired.

The section 10 may constitute duct impregnated to render the same impermeable to air or may be sections

of woven asbestos fabric, also suitably treated to make the same relatively impermeable to the flow of gas therethrough, as well known in the air conditioning and heating and ventilating fields, and as described in my aforesaid application, by way of example.

The metal chosen is in accordance with that used in the heating and ventilating field for making ducts and may utilize galvanized sheet iron of at least 24 to 28 gauge thickness, though for small duct sizes a lesser thickness may be employed.

For purposes of illustration, the fabric 10 may be of an initial width of five inches and of extended length of from fifty to one hundred feet. Strips 11 and 12 are each at least more than one-half of the width of the fabric 10, and preferably one strip is of greater width than the other. For purposes of illustration, the strips may be four inches and five inches, respectively, and each is formed adjacent the side edges 13 and 14 with slotted cutout portions 15 of oblong outline, the length of which oblong is at least twice the overhang 16 between the outer edge walls 17 and 18 and the side edges 13 and 14, respectively. The width of the oblong is preferably, though not necessarily, large enough to provide clearance for the blade of a metal snipper. Where the slots 15 are made by a punching die, which is preferred, the burrs 15a are left to extend in the same facial direction for each strip 11 and 12, to provide a more intimate fabric engagement when pressed into engagement with the same.

With lengths of strips 10, 11 and 12 so provided, the leading edges 19, 20 and 21 of the three components are joined with the strips 11 and 12, overlapped at their edges 22, 23 for a distance to space the same so that the edges 17 and 18 are aligned with the side edges 24, 25 of the fabric 10. In this position, the edges 13 and 14 are given a first fold 26, 27, as shown in FIGURE 2, and then a second fold 28, 29, to form a tubular convolute of more than one turn, in the illustration providing a turn and a half of three layers of sheet metal and fabric except at the notched out portions 15.

Flattening the convolute to press the layers into intimate engagement at the folds will direct the burrs 15a previously described into greater frictional face engagement with the fabric. The width of the scoring with relation to the folded-in portion or overhang 16 extends diametrically across the convolute, to expose only two layers of sheet metal between the remnants of metal 30 effected by the scoring 15. The spacing 31 defined by the scores 15 is of a nature to permit entry of the blade of hand snips to cut off or fashion the composite in the further procedure of converting a length of stock into a duct, and thereby facilitate this tiresome operation.

When formed into short or indeterminate lengths of fifty to one hundred feet, with the metal layers overlapping each other and both under the overlying fabric as a three layered component, the product may be packaged flat or in coils, as described in my prior application. When formed into coils, the differential thickness does not result in adverse warping or produce a permanent set by reason of the flexibility in forming the double folded edge with transverse scores or notches and packaged coils may be reduced in size. For instance, a coil of one hundred feet in length of 24 to 26 gauge metal, in accordance with my invention, may be packaged in a twenty-four inch square box, five to six inches deep, as compared with the necessity for using a thirty-six inch box for an un-scored coil of similar length and gauge, in accordance with my prior application.

The space saving factor not only effects economies in storage and transportation but facilitates ease of handling due to the reduced bulk so that one individual may handle a carton as compared with the necessity for handling of the larger size carton by two workmen. Coiling to the smaller dimension is possible without effecting waviness or distortion. A cut off length will quickly lie flat and may be readily worked and be bent to sharp cor-

ners on a bending brake, without rupturing the fabric, and in fact permitting the use of bending brakes to make corners of an angularity which normally would weaken the fabric.

When bent along the cross notches, the composite will furnish sharp cornered duct outlines without requiring an undue amount of malleting or bending dies to square up a corner. Forming inside folds (see FIGURE 8) or outside folds (see FIGURE 9) of the fabric in the formation of the duct of oblong outline O, or cylindrical outline C collars does not relax the clinched condition of the folds of metal and fabric in differential contraction due to the thickness of layers. Where the burrs 15a are formed by punching dies in making the notches 15, finishing operations to remove the burrs are unnecessary as the burrs enhance the grip between the fabric and the metal in flattening the folds of metal and fabric and condensing the enfolded fabric in clinching the folds.

The product aforementioned may be made in limited lengths or extended lengths and stacked flat, one layer superimposed on another, or made in continuous lengths of from fifty to one hundred feet for handling, as described in my prior application, in coils. The employment of scored or notched blanks for making the composite has certain additional advantages and may be conveniently produced by procedure and apparatus which will now be described.

For this purpose, reference is made to FIGURES 10 to 21. In this assembly, raw stock for the strips 11 and 12 is supplied in the form of tightly wound coils A and B, respectively, of the metal, which are fed to a double punch 32 in side by side relationship, to punch the scores or cutouts 15 in an adjacent relationship to concentrate the punch power.

A long, loose hanging flight 33 is provided beyond the punching zone which permits the strips 11 and 12 to be crossed over each other and reversed two ways from side by side position to another so that the scores or cutouts 15 are positioned remote from each other instead of being adjacent to each other as at the punching operation, and to position the lower faces so that they are upwardly directed. The burrs formed incident to the punching operation, which were downwardly disposed at the punch zone, thus are also upwardly faced. The strips are then overlapped, as shown in FIGURE 1, with relation to a width of duct sealing fabric and the leading edges fixedly secured together, as by riveting or spot welding, so as to enter the hold down rollers 34 in a predetermined spaced apart, overlapped position, where the mated strips 11 and 12 are guided upon the platen 35, having side channel guides 36, 36a. The hold down rollers 34 optionally may, if desired, have interfitting sprockets for engaging the scores or cutouts 15, to coordinate movement of the independent strips in unison without any relative differential movement. Suitable adjustable means (not shown) for urging the rollers into pressure engagement in accordance with the thickness of the composite of metal may be employed, as will be readily understood, and this arrangement is effected for all of the journal boxes for the shafts of all of the guides or forming rolls in accordance with sound practice.

The side 13 of the strip 11 is thereby guided in abutting relation to the upstanding channel flange 36a and the side edge 14 of the strip 12 is abutted against the upstanding channel flange 36. Thereupon the strip enters between opposed pairs of aligning mated rollers 37, 37a and 38, 38a, which grip the strips 11 and 12 through cutouts 39 in the platen 35, as shown in FIGURE 12.

The aligning mating rolls 37 and 38, and 37a and 38a, are of the same diameter and are preferably, although not necessarily, held on the common shafts. The rolls are free rolling on their common shafts 40 and 41. Ball bearing rollers (not shown) with inner and outer races are provided, the rolls rotating on the inner races. The shafts are fixedly mounted and do not rotate. The inter-

engaging mating rolls 37 and 38, 37a and 38a are designed to maintain the edges 13 and 14 in diverging relation and in pressure contact with the upstanding channel guides 36a and 36, respectively, beneath the hold down brackets 36b. This is effected by providing toe-in or leading edge camber to the rolls and by bending the shafts 40 and 41 in a small angle, say $2\frac{1}{2}^\circ$. The continuing outward pressure against the accurately parallel, upstanding channel of guides 36a and 36 thereby avoids any inaccuracy of variance in width of the strips 11 and 12, which overlap sufficiently (the amount of overlap short of reaching the opposite edge being immaterial) and at the same time, by use of the series of forming rolls to be described, avoiding any guides whatever at an intermediate point, assure an accurate spaced relationship between the edges 13 and 14 of the strips in the further processing of the strips.

The strips 11 and 12 then proceed to engagement between pairs of metering mating rolls 42, 42a below and above the platen or bed 35. The metering rolls 42 and 42a are cylindrical and are truly square with relation to the axial line of endwisely journaled upper and lower connecting shafts 43, to which the metering rolls 42 and 42a are keyed, to rotate the upper face rolls 42, 42a in unison and the lower face rolls 42 and 42a in unison. However, the shaft coupled rolls 42, 42a may be of differential diameter, depending upon whether the ultimate product is being packaged flat or in coils. Where the product is to be packaged in coils, I have devised means for assuring a length of the metal strips and fabric to be unwarped, when coiled and then uncoiled, by a reduction in the peripheral feed of the metering rolls 42a. This is accomplished by turning down the metering rolls 42a so that they have a peripheral length of one and one half inches less per one hundred feet than the metering rolls 42, with a 24 gauge stock of sheeting, as an example. Variations in coil characteristics, i.e., number of convolutions and length of stock with different thickness of metal and different thickness of fabric, will require variations in the differential between the pairs of metering rolls and machine design to meet the changed conditions, will accordingly now be apparent.

The strips then pass between hold down plates 44, after which they are fed below the guide roll 45, where they meet the flight of duct sealing web of fabric 10 fed thereto from the roller R over the guide rolls 46 to taunt the same.

The web of fabric 10 is centered with regard to the overlapping strips 11 and 12 so that the overhang 16, previously described, projects to each side edge of the fabric or selvage edge of the fabric, where a selvaged edge fabric is employed. For a five inch width fabric, the plates are positioned so that the edges 13 and 14 are spaced apart so that each gives an overhang of approximately five-sixteenths of an inch, and press the fabric completely to cover the scores or cutouts 15 and into engagement with the upstanding burrs 15a, and to compact the fabric to secure engagement. A three layered flat composite is then fed into the spaced-apart parallel series of mated upper and lower forming rolls, nine double groups being shown, where the double fold edges are impressed on the composite to form a flattened convolute of one and one-half turns, pairs of upper and lower forming rolls 47, 47 and 47a, 47a impressing upon the edges 13 and 14, respectively, a 45° bend adjacent the weakened line of fold of the innermost wall of the cutouts 15, to engulf the edges 24 and 25 of the fabric 10. The provision of common, integrated shafts for the laterally spaced rolls and coupling for the mated forming rolls will be understood as desirable to assure uniformity, and therefore have not been illustrated.

The web then passes through pairs of mated upper and lower forming rolls 48, 48 and 48a, 48a, shown in FIGURE 14, where the edges 13 and 14 are given a further 45° bend, to bring the same to 90° . Pairs of upper and

lower mated forming rolls 49, 49 and 49a, 49a bend the overhang to 135° , as shown in FIGURE 15. Pairs of upper and lower mated fold rolls 50, 50 and 50a, 50a, as shown in FIGURE 16, form the overhang edge into the first fold 26, 27, and clinch the metal into engagement with the fabric. Thereupon the composite is fed to pairs of upper and lower mated rolls 51, 51, 51a, 51a, in which the first fold is bent 30° , as shown in FIGURE 17. Thereupon the composite moves to pairs of upper and lower mated rolls 52, 52, 52a, 52a, where the first fold is given a further bend of 30° , as shown in FIGURE 18. Thereupon, the composite moves to pairs of upper and lower mated rolls 53, 53, 53a, 53a, where the first fold is given an additional bend to 90° , as shown in FIGURE 19. Thereupon the composite moves to pairs of upper and lower mated rolls 54, 54, 54a, 54a, where the first fold is bent to an angle of 135° , FIGURE 20. Then the composite moves to pairs of upper and lower mated rolls 55, 55, 55a, 55a, where the first fold is bent 180° , FIGURE 21, to flatten and clinch the edges to the final convolute.

Each of the cooperating upper and lower rolls 47 to 55 which form the edge fold 29, maintains a differential peripheral length as compared with the series of rolls 47a to 55a, which form the double fold 28, to have the fold 29 of lesser peripheral length than the edge fold 28, thereby assuring a linear arrangement of the composite web at its side edges without any warping or camber or evidencing objectionable buckling when the finished product is coiled and uncoiled. As the length is fed into mating end guide rolls 56, 57 at the zone 58, periodic shearing may be effected by the shears 59 as the length is fed to a take-up creel where a core may be located, or a take-up linear chain carrier 60. Where a take-up carrier is employed, the composite may be stored flat in lengths of one hundred feet to be used from this source, or then wound into coils about a core which will provide an outer diameter of coil of twenty-four inches for such length, thereby permitting storage in a two foot square carton as compared with a three foot square carton for similar gauge metal and length of strip in previous packages. Such close coiling is made possible from flat stock or creel stock at the station 60 without creating any permanent set in the composite when it is ready for use in the field, and has the advantages previously described as to flexibility, trueness of alignment and freedom from waviness.

The notched portions or scores provide weakened lines of fold, minimizing the stresses for making the folds and facilitating a pacing of the strips 11 and 12 to prevent differential stressing or crowding of the length of the composite occasioned by the overlapping and the multi-layers which have been convoluted into the double folds. Benefits inure from the simultaneous folding operation of three composites in avoiding objectionable differential length or camber or warping as well as in permitting a creeling at the zone 60, with less tension components in making a coil of relatively small diameter. Yieldability by reason of the slotted or scored portions 15 permits tight coil creeling directly from the forming rolls or from stored continuous straight lengths of the composite, with the assurance that when the packaged coil is unrolled, lengths may be severed without waste.

I have not specifically shown the coupling of the shafts of the various mated feeding and forming rolls which have the ends of their supporting drive shafts extended and provided with suitable drive gears which are coupled to suitable driving means to assure powerized rotation in coordinated relation, to cause the composite stock to move in unison to the stock take-up means, such as a creel or a rectilinear extended chain carrier where continuous lengths of from fifty to one hundred feet are collected in the flat, preparatory to packaging in short lengths or in coils to provide a closely wound coil of about 24

inches in diameter, as described, for a one hundred foot length.

By my invention, substantial economies are effected in packaging, storage, handling, labor and working conditions, while producing a better quality product than described in my prior application.

While I have exemplified one form of my invention, it will be understood that modification will now readily become apparent and that the scope of my invention is to be broadly construed.

Having thus described my invention and illustrated its use, what I claim as new and desire to secure by Letters Patent is:

1. A flexible duct connector stock for joining the edges of ducts comprising two elongated sheet metal strips and a length of duct sealing fabric, said strips each having a side marginal portion folded over toward the strip and clampingly engaging a different side edge of said length of fabric to sandwich said side edge of said fabric between said folded over portion and a part of said strip, 15 said folded over portions and said parts each having longitudinally spaced apart, transversely extending slots, the outline of said slots being defined by sharp burred elements extending beyond the plane of one face of said strips, said one face forming the inside of said fold whereby said burred elements are driven into both surfaces of said fabric upon formation of said clamping fold and thereby augment the engagement of said strips and said fabric, said fabric, after folding of said strips, serving to seal said slots of said strips.

2. A connector in accordance with claim 1 wherein said slots are of a greater transverse than longitudinal dimension.

5

3. A connector in accordance with claim 1 wherein said side marginal edge portions are doubly folded over whereby two layers of said fabric are clamped between three layers of said strips.
